(57) **CLAIM**

The ornamental design for an air fryer as shown and described.

DESCRIPTION

FIG. 1 is a perspective view showing an air fryer design; FIG. 2 is a front elevational view of the air fryer shown in FIG. 1;

FIG. 3 is a rear elevational view of the air fryer shown in FIG. 1;

FIG. 4 is a right side elevational view of the air fryer shown in FIG. 1;

FIG. 5 is a left side elevational view of the air fryer shown in FIG. 1;

FIG. 6 is a top plan view of the air fryer shown in FIG. 1;

FIG. 7 is a bottom plan view of the air fryer shown in FIG. 1;

FIG. 8 is a perspective view showing a second embodiment of an air fryer design;

FIG. 9 is a front elevational view of the air fryer shown in FIG. 8;

FIG. 10 is a rear elevational view of the air fryer shown in FIG. 8;

FIG. 11 is a right side elevational view of the air fryer shown in FIG. 8;

(Continued)

FIG. 12 is a left side elevational view of the air fryer shown in FIG. 8;

FIG. 13 is a top plan view of the air fryer shown in FIG. 8; and,

FIG. 14 is a bottom plan view of the air fryer shown in FIG. 8.

The invention is an air fryer as shown in FIGS. 1-14, where FIGS. 1-7 illustrate a first embodiment of the air fryer and FIGS. 8-14 illustrate a second embodiment of the air fryer. The portions of the air fryer shown in broken lines are included for the purpose of illustrating unclaimed portions of the air fryer and form no part of the claimed design.
